UNITED STATES PATENT OFFICE.

ALBERT H. McALLISTER, OF NEW ALBANY, MISSISSIPPI.

DESIGN FOR A NUT-LOCK WASHER.

SPECIFICATION forming part of Design No. 33,693, dated December 11, 1900.

Application filed November 10, 1900, Serial No. 36,137. Term of patent 3½ years.

To all whom it may concern:

Be it known that I, ALBERT H. McALLISTER, a citizen of the United States, residing at New Albany, in the county of Union and State 5 of Mississippi, have invented and produced a new and original Design for a Nut-Lock Washer, of which the following is a specification, reference being had to the accompanying drawings, forming a part thereof.

10 Figure 1 shows one of the broader faces of the nut-lock washer. Fig. 2 is a section on the line 2 2, Fig. 1.

15 The configuration or outline of the nut-lock washer, as seen in the two views, constitutes the leading or material feature of my novel design.

20 As appears from Fig. 1, the nut-lock washer is in outline a quadrilateral having its base longer than the side opposite the base and having a large perforation A, approximately equidistant from the base B and the sides C

D adjacent to the base. That part E above the line F, approximately parallel to the base, is inclined from the plane passing through said base and line F, and the middle portion 25 of the part between the base and line F is bent in the same direction from said plane, as clearly appears in Fig. 2, so that the part closely adjacent to the perforation is at some distance from said plane. 30

Having described my invention, what I claim as new, and desire to secure by Letters Patent, is—

35 The design for a nut-lock washer as herein shown and described.

In testimony whereof I affix my signature in presence of two witnesses.

A. H. McALLISTER.
